Patented May 16, 1922.

UNITED STATES PATENT OFFICE.

CYRUS T. WHALEY, OF NORFOLK, VIRGINIA.

TROLLEY GUARD FOR TUNNELS.

1,416,585.

Specification of Letters Patent. Patented May 16, 1922.

Application filed October 17, 1921. Serial No. 508,052.

To all whom it may concern:

Be it known that I, CYRUS T. WHALEY, a citizen of the United States, residing at Norfolk, in the county of Norfolk and State of Virginia, have invented certain new and useful Improvements in Trolley Guards for Tunnels, of which the following is a specification.

This invention relates to overhead trolley guards and has special reference to a tunnel guard for trolleys.

One important object of the invention is the provision of an improved and simple device for guiding the wheel of an overhead trolley through a tunnel in such a manner as to positively prevent any possibility of the trolley becoming displaced from the guide in the tunnel.

A second important object of the invention is the provision of an improved arrangement of this character particularly adapted to be applied to the trolley wires of electric railways without in any way altering the position of such wires.

With the above and other objects in view, the invention consists in general of certain novel details of construction and combinations of parts hereinafter fully described, illustrated in the accompanying drawings, and specifically claimed.

In the accompanying drawings, like characters of reference indicate like parts in the several views, and:—

Figure 1 is a perspective view of a tunnel entrance showing the improved guide or guard in position.

Figure 2 is a perspective view on a large scale of a portion of this improved guide or guard in a slightly modified form.

Figure 3 is a transverse section of the guard shown in Figure 1.

Figure 4 is a detail view showing a portion of the side of Figure 3.

Figure 5 is a detail section on the line 45 5—5 of Figure 3.

Figure 6 is a plan view showing a curved arrangement of guard.

In the embodiments of the invention herein illustrated two forms are shown. In the form shown in Figures 1, 3, and 4, the guard is built up of three distinct members with suitable clips to hold them in position. In this form there is provided a clip having a horizontal portion 10 provided at each end with eyes 11 for the suspension wires of the device. The wires 12 may be attached

to poles 13 or to suitable eyes or hangers 14 within the tunnel. Depending from the horizontal portion 10 are downwardly extending legs 15 and these legs carry parallel vertical side members 16 secured to the legs by bolts 17. These side members are so arranged that the distance between the side members is slightly greater than the width of a trolley wheel W. Secured to the central portion of the clip top 10 by bolts 18 is a top member 19 having a longitudinally extending trough 20 receiving the trolley wire W', the wire being held in the trough by the top member of the clips. At each end of the structure the member 19 is tapered upward as at 21 so that a trolley wheel approaching the guard on the wire W' will roll off this wire into the trough without shock or jar.

In the form of the device shown in Figure 2 the guard has its sides 22 and top 23 formed integral, the top being provided, as in the other case with a trough 24 for the reception of the trolley wire W'. In this case the trolley wire is held in the trough by means of suitable transverse clips 25 secured over the wire by bolts 26. Formed integrally with the guard are suspension ears 27 to which the wires 12 may be connected as in the other case.

It is to be observed that in each instance the structure is of an inverted channel shape with the web of the channel bulging downward centrally. It is also to be observed that this downwardly bulged web is engaged by the flanges of the trolley wheel W and by reason of its shape the trolley wheel is held centrally of the channel.

There has thus been provided a simple and efficient device of the kind described and for the purpose specified.

Having thus described the invention, what is claimed as new, is:

1. In a device of the kind described, a guard member consisting of an inverted channel having its sides spaced to receive a trolley wheel between them, the web of the channel being downwardly concave between said sides to provide contact means for the flanges of the trolley wheel.

2. In a device of the kind described, a guard member consisting of an inverted channel having its sides spaced to receive a trolley wheel between them, the web of the channel being downwardly concave between said sides to provide contact means for the flanges of the trolley wheel, the upper face

of said web being provided with a longitudinal trough to receive a trolley wire, and means to hold the wire within the trough and to provide supporting wire attaching elements.

3. In a device of the kind described, a clip consisting of a horizontal top member provided with attaching wire receiving ears at its ends and having a pair of spaced depending legs, and an inverted channel shaped guide consisting of side plates ar-

ranged in spaced relation and supported on the legs of said clips and a top plate supported between the legs of said clip and provided with a transversely convex under 15 surface and a trolley wire receiving trough in its upper surface, the central portion of the clip extending across said trough to constitute retaining means for the wire.

In testimony whereof I affix my signature. 20

CYRUS T. WHALEY.
